GARMENT CONSTRUCTION

Perkins H. Bailey, New York, N. Y., assignor to
Talon, Inc., a corporation of Pennsylvania

Application March 29, 1940, Serial No. 326,705

1 Claim. (Cl. 2—76)

This invention relates to garments and, in particular, to the provision of improved front constructions in such garments, for instance, as are known as "housecoats" and "housedresses."

It is the primary object of this invention to provide such constructions embodying the features of low cost, attractive appearance, utmost ease and facility of ingress and egress, and convenience in adjusting the garments to forms or figures of widely varying sizes and proportions.

It is a further object of this invention to provide such constructions embodying a slide-fastened closure, which is of relatively short length with respect to the length of the complete garment front opening provided by the garment front construction.

It is a further object of this invention to provide such constructions wherein an opening, in the front waist portion of the garment, is provided with a separating end slide fastener leading into an opening, adjacent and below the garment waistline, which last-named opening provides for extension of the slide-fastened closure throughout the length of the garment.

It is a further object of this invention to provide such constructions wherein the opening, which provides an extension of the slide-fastened closure, is closed by a transverse overlapping of the skirt portion of the garment.

It is a further object of this invention to provide such constructions wherein one flap provided by overlapping of the garment skirt portion is disposed in lapped relationship with respect to the lower, separating end of the fastener in the slide-fastened closure of the garment waist portion, and in like relationship with respect to the adjacent lower end portions of the garment waist portion.

It is a further object of this invention to provide such constructions wherein the outer flap provided by overlapping of the garment skirt portion is provided with tie string means adapted for retaining the flap in closed position while, at the same time, providing means for adjusting the waistline portion of the garment to waistlines of widely varying sizes.

It is a further object of this invention to provide such a construction wherein the lower end of the fastener, in the slide-fastened closure, is substantially free and readily accessible for facilitating manual disconnection of the lower ends of the slide fastener in opening the slide-fastened closure.

These and other objects and advantages of the invention will appear from the following descrip-

tion taken in conjunction with the accompanying drawing which forms a part thereof, and will be pointed out in the appended claim.

In the drawing:

Fig. 1 is a front view of an illustrative garment embodying a garment front construction, according to this invention, with the garment front closed;

Fig. 2 is a fragmentary view of the garment front construction of Fig. 1, with the garment front closure partly open;

Fig. 3 is a fragmentary front view of an illustrative modified form of garment construction, the garment front closure being closed, and a part of the garment skirt portion being omitted in the interest of clearness of disclosure;

Fig. 4 is a view similar to Fig. 2 of the modified garment construction illustrated in Fig. 3; and

Fig. 5 is a rear view of the illustrative garment construction of Figs. 1 to 4 inclusive, the lower part of the garment skirt portion being omitted, as in Figs. 2, 3 and 4.

This invention extends the use of slide fasteners to low cost garments such as "housecoats" and "housedresses," of the "wrap around" type, wherein the use of other fastening means has formerly been dictated by the extremely rigid price restrictions imposed by the highly competitive nature of the low cost garment market.

Formerly, in the manufacture of garments such as "housecoats" and "housedresses," the provision therein of slide-fastened closures of such length as to provide the necessary and desirable large opening necessary for convenience of ingress and egress, has been accomplished only with the accompanying disadvantages of substantial, if not prohibitive, increase in garment cost. This has been particularly true in the highly competitive low cost garment field, where the increase of the price of a garment by a few cents has, quite often, been disastrous to the manufacturer of the garment in this highly competitive field.

Slide fasteners are sold by length and, for that reason, the use of a fastener of such length as to extend throughout the length of a closure of from 36" to 40", hitherto thought necessary for convenient ingress and egress, made the price of the slide fastener a substantial, if not exorbitant, factor in the sale price of the garment.

According to this invention, a relatively short slide-fastened closure incorporating a slide fastener of short length and, therefore, of low cost, is used in the waist portion of the garment. An extension of the slide-fastened closure opening

is provided in the skirt portion of the garment and flap or apron means is provided for closing the extension of the slide-fastened closure opening. This structure achieves, by the use of a cheap slide fastener of short length, the advantages achievable heretofore only by the use of slide fasteners of far greater length and commensurately greater cost.

Considered in a different way, the front of the garment is provided with a closure opening of such length as to achieve the necessary and desirable convenience of ingress and egress. A part only of this closure opening is slide-fastened by the use of a short cheap separating end slide fastener. That portion of the closure opening which is not slide-fastened, is closed by a flap or apron in the skirt portion of the garment and provided with means for retaining it in overlying relationship with respect to that portion of the closure opening is not slide-fastened. The retaining means preferably functions also as garment waist adjusting means.

By the above, generally described structure, the above enumerated objects and advantages are achieved, as will be hereinafter pointed out in detail.

In the following description, for the sake of convenience, the rear portion of the garment extending downwardly from the upper end or neck thereof to the bottom of the skirt and from side to side, will be treated as a unit and designated the back panel. This back panel may, of course, be formed of a single piece of material or of a plurality of pieces of material secured together in any known manner.

That part of the front wall of the garment which forms the front wall of the waist portion of the garment and which extends from the upper end or neck of the garment downwardly to the waistline of the garment, at least, and from side to side thereof, will be considered as a unit and designated the front waist panel. This front waist panel may, of course, be formed of a single piece of material or made up of a plurality of pieces of material secured together in any known manner. The front waist panel is provided with a slide-fastened closure extending from its upper end to its lower end and located between the side edges thereof.

The other part of the front wall of the garment, extending upwardly from the bottom of the garment to the waistline, at least, and from side to side of the garment, will be designated the front skirt panel. This front skirt panel forms the front wall of the skirt portion of the garment.

Conventional details of dressmaking, such as stitching, seams, facings, and the like, which are not in themselves a part of this invention, will be omitted from the following description and are omitted from the drawing of this application in interest of clearness of disclosure.

Referring to the drawing in detail and with reference to Figures 1 to 5, the back panel is generally designated 10, the front waist panel is generally designated 11, and the front skirt panel is generally designated 12.

In the embodiment illustrated in Figs. 1 and 2, the front waist panel comprises a pair of panel portions 14 and 15, each having its outer edge secured in suitable manner to an adjacent edge of the back panel 10. The lower end portions of the panel portions 14 and 15 are free to form flaps 14a and 15a which serve a purpose hereinafter described in detail.

The front skirt panel 12 is in the form of a flap extending from the waistline to the bottom of the garment and having one edge secured throughout its length to an adjacent edge of the back panel 10. At its upper end, the upper edge of the front skirt panel is secured to the front waist panel 11 from that edge which is secured to the back panel 10 substantially to the middle of the front of the garment.

The remainder of the front skirt panel 12 is free and forms a flap 16 which extends to, and preferably beyond, the other side of the garment. Preferably, the back panel 10 is extended, in the skirt portion, beyond this last-mentioned side of the garment forwardly under the flap 16, substantially to the central portion of the garment to form an under-flap 10a which is overlapped by the flap 16. From the above, it will clearly appear that the underflap 10a may be integral with the back panel 10 or attached thereto in suitable manner.

In order to secure the flap 16 in closed position, where it overlaps the under-flap 10a, for closing the closure provided between the under-flap 10a and the front skirt panel 12, a pair of ties or tie members 20 is provided. One of these tie members is secured to the upper end of the free edge of the flap 16 and the other is secured at the upper end of the inner, secured edge of the front skirt panel 12. These ties 20 are extended about the waist portion of the back panel 10 and knotted together, as shown in Fig. 5, to secure the flap 16 of the front skirt panel 12 in closed position and also to provide adjustment for the waist of the garment.

As will readily be seen in Fig. 1, the flap portions 14a and 15a extend downwardly in overlapping relationship over the upper end of the front skirt panel 12 in such manner as to make the details of the front disclosure imperceptible to an observer.

The front waist panel 11 is provided with a slide-fastened closure which comprises a pair of stringers of a slide fastener 17 having a separating end fitting 18 and a slider 19, one stringer being secured to the inner edge of the front panel portion 14 and the other stringer being secured to the corresponding edge of the front waist panel portion 15.

As may be readily seen from Figs. 1 and 2, the extension of the slide fastener 17 to the lower end of the front waist panel 11, which locates the separating end fitting 18 between the flap portions 14a and 15a, provides ultimate freedom of access to the separating end fitting for facilitating opening and closing of the slide-fastened closure in the front waist panel 11 by connecting and disconnecting the stringers of the slide fastener 17. The wrap-around skirt portion of the garment has a closure therein which provides an extension of the slide-fastened closure from the waist portion of the garment to the lower end thereof. This closure in the garment skirt portion is also at all times effectively closed by the substantial overlapping relationship between the flap 16 and the underflap 10a.

In the embodiment illustrated in Figs. 3 and 4, the side edges of the back panel 10 are disposed but slightly beyond the sides of the garment, as shown in Fig. 4. The front waist panel portions 14 and 15 terminate substantially at the waistline of the garment, and the flap portions 14a and 15a are omitted therefrom.

The front skirt panel 12 has a waist band 12a incorporated in its upper edge from the opposite

ends of which the ties 20 extend, as shown in Fig. 4. These ties are extended over the back panel 10 at the waistline of the garment and knotted, as shown in Fig. 5.

One side edge of the front skirt panel 12 is secured to the back panel 10 from the upper end to the lower end of the front skirt panel 12 with the edges of the front skirt panel and the adjacent side of the back panel in slightly overlapped relationship.

The waist band 12a is secured to the front waist panel 11 from the same side of the back panel 10 substantially to the slide-fastened closure at the central portion of the front waist panel 11.

The width of the front skirt panel 12 is substantially greater than the distance between the edges of the back panel 10 whereby the front skirt panel 12, at its free edge, extends around over the back panel 10 of the garment to provide substantial overlapping of the flap 16 over the adjacent side of the back panel 10. This flap 16 is formed by the free portion of the front skirt panel 12 beyond that portion thereof which is secured to the front waist panel by attachment of the waist band 12a thereto, as described above.

The above-described embodiments are illustrative of the application of the principles described in my copending application Serial No. 325,992, filed Mar. 26, 1940, to garments of the wrap-around type as distinguished from the types of garments described in that application.

It is, of course, to be understood that the above-described structure is merely illustrative and in

nowise limiting and that I desire to comprehend within my invention all modifications included within the scope of the appended claim.

Having thus fully described my invention, what I claim as new and desire to secure by Letters Patent is:

In a garment including a back panel coextensive with the length and width of said garment, a front waist panel secured at its upper and side edges to said back panel, a front skirt panel secured at one side edge to the adjacent side edge of said back panel and having a substantial portion of its upper end free of attachment to said front waist panel, said front waist panel having a front opening extending throughout its length, a separating end slide fastener secured to said front waist panel at the opposite sides of said opening and terminating substantially at the waist portion of the garment, the freedom of the free portion of said front skirt panel providing a flap portion overlying the portion of said front opening below said slide fastener, and the free upper end of said front skirt panel and the lower end portion of said front waist panel being in lapped relationship, and the point of attachment of said front skirt panel to said front waist panel being spaced upwardly of the lower edge of said front waist panel, at its underside, to provide a flap overlapping the front end of said front skirt panel and providing free manual access to the separating end of said slide fastener.

PERKINS H. BAILEY.
